UNITED STATES PATENT OFFICE.

MATTHEW G. BALFOUR, OF MASON CITY, IOWA.

IMPROVEMENT IN ELEVATORS CONNECTED TO WAGON-BODIES.

Specification forming part of Letters Patent No. 124,531, dated March 12, 1872.

To all whom it may concern:

Be it known that I, MATTHEW G. BALFOUR, of Mason City, in the county of Cerro Gordo and State of Iowa, have made certain new and useful Improvements in Elevating Tail-Boards for Wagons, of which the following is a specification, reference being had to the accompanying drawing.

Nature and Object of the Invention.

The invention relates to providing the rear of a wagon-body with a hinged tail-board, which is connected to the wagon-body by means of chains passing over pulleys hung in apertures in ears on the upper part of the body, and secured to a revolving shaft provided with a crank-pawl and ratchet-wheel, which shaft being operated the chain is let out or drawn up, thus lowering or elevating the tail-board. The object of the invention is to provide a wagon-body with a device, by means of which articles can be loaded upon or unloaded from it with facility.

Description of the Accompanying Drawing.

Figure 1 is a side view of the device, illustrating the operation of elevating a package. Fig. 2 is a similar view of same, showing the manner of securing the tail-board to the end of the wagon-body.

General Description.

A in the accompanying drawing represents a wagon-body, the extreme rear ends of the sides of which are so inclined that the upper corners or points thereof project beyond the ends of the bottom of the wagon-body, which, however, exceeds in length the lower edges of the sides to an extent equal to the thickness of the tail-board, so as to afford a support therefor. To the outside of the wagon-body, immediately adjacent to the said inclined ends, is secured the strap B, the upper extremities of which are provided with the eyes Z, which project to the rear beyond and stand out on opposite sides from the upper part of the wagon-body, to which the straps B are attached. At the lower extremities of these straps are provided the pawls C, which engage the teeth of the ratchet-wheels D when the ratchet is moved

toward the pawls. The shaft E revolves in journals fixed to the under side of the bottom of the wagon-body A, its extreme ends x having angular sides so as to be operated by a crank or wrench. Adjacent to these ends are the collars F, between which and the ratchets D the chains H are secured and received when wound up. These chains pass over concaves or flanged pulley-wheels I in the blocks L, provided with the hooks M. The other ends of the chains are secured to rings N, which connect the rings in the extremities of the rods O. The other ends of the rods are hooked into the eyes in the ends of the ears P, which are properly secured to the sides and back of the tail-board R, which is of proper dimensions, and hinged at its longitudinal center so as to partially close when the chains are drawn taut, and thus prevent any article rolling off the tail-board while being elevated. When the device is not in operation the blocks L may be hung by the hooks M in the eyes on the pieces S. The tail-board R is secured at the rear end of the wagon-body, being held by the chains H being drawn taut, the hooks M having been placed in the eyes on the pieces S.

It is obvious that the invention can be applied to a wagon-body similarly provided, but having vertical instead of inclined edges at its rear, it being only necessary to have the eyes Z project a proper distance rearward.

Operation.

Raise the pawls C; place the hooks M in the eyes Z in the ends of the straps B; remove the tail-board R from its place and turn the shaft E so as to lower the tail-board to the desired position; place the article to be elevated upon the tail-board; drop the pawls C; turn the shaft E so as to wind up the chains which elevate the tail-board R to the level of the bottom of the wagon-bed, upon which the article may then be moved. As the chains H are drawn taut, the tail-board being hinged at its center, its upper and lower edges are raised above its center, thus preventing the article on the tail-board slipping or rolling off of it.

It is obvious that the tail-board can be suspended at any point by allowing the pawls to engage the ratchet-wheels, which prevents the

chains H running out, and thus holds the tail-board R suspended.

Claims.

What I claim as my invention, and desire to secure by Letters Patent, is—

1. The hinged tail-board R, substantially as shown and described.

2. The hinged tail-board R, provided with the rods O, in combination with the chains H, eyes Z, block L, pawl C, shaft E provided with

the ratchet-wheel D, for the uses and purposes substantially as shown and described.

In testimony that I claim the foregoing invention of improvements in elevating tail-boards for wagons, as above described, I have herenunto set my hand and seal this 22d day of January, 1872.

MATTHEW G. BALFOUR. [L. S.]
